FIG. 5.

INVENTOR
Harold D. Allen,
BY
Loft Bonker
ATTORNEY

UNITED STATES PATENT OFFICE.

HAROLD D. ALLEN, OF EAST HAMPTON, CONNECTICUT, ASSIGNOR TO THE GONG BELL MANUFACTURING COMPANY, OF EAST HAMPTON, CONNECTICUT, A CORPORATION OF CONNECTICUT.

TOY PHONE.

Application filed July 21, 1922. Serial No. 576,456.

To all whom it may concern:

Be it known that I, HAROLD D. ALLEN, a citizen of the United States, and a resident of East Hampton, in the county of Middlesex and State of Connecticut, have invented certain new and useful Improvements in Toy Phones, of which the following is a full, clear, and exact description, whereby anyone skilled in the art may make and use the same.

10 The invention relates to toys and particularly to a toy of the telephone type which simulates, in some respects, the radio telephone, in that it has a head piece or clamp and receivers which may be adjusted to the 15 ear.

It is designed particularly to be used as an amusing toy for children over which the voice may be transmitted; and while not being directed to the commercial type of 20 telephone, has certain features which will appeal to the child and permit transmission of sound waves.

The object of the invention is to provide a simple toy which will have certain features 25 of the standard telephone transmitting and receiving sets and will enable the child to play at receiving and sending messages.

A further object is to provide a sounding 30 device, the manipulation of which will give a clear tone signal in simulation of that employed on the usual commercial telephone set.

Referring to the drawings:

Figure 1, is a view in side elevation with 35 the transmitter and receiver elements broken in section.

Figure 2, is a front face view of the features illustrated in Figure 1.

Figure 3, is a view in elevation of the 40 head piece and attached receivers.

Figure 4, is a fragmentary view illustrating the clamp device by which the receivers are adjusted.

Figure 5, is a diagrammatic view illustrating the head clamp and receivers in connection with a transmitting telephone set.

Toy telephones having signalling devices are not new in the art nor is it new in the art to provide a receiving and sending de-

vice in a toy with a connecting wire or cord 50 over which sound vibrations may be transmitted.

The present invention differs from this prior art in that it provides a head piece with means for ready adjustment in connection with a bell toy telephone transmitter which will permit children to utilize the device in simulation of the sending and receiving elements of a radio phone.

Referring to the drawings, numeral 1, denotes a hand piece or post upon which is mounted a cap 2, to which is secured a plate 3, supporting the transmitter 4.

The transmitter consists of a mouthpiece 5, and a sound chamber having a front plate 6, and a rear plate 7. These plates are stamped or spun up from sheet metal and are clamped together as at 8, to secure a diaphragm 9.

The rear member of the chamber 7, has 70 an opening 10, and to stiffen the rear wall thereof, plates 11, 12, also perforated, are secured by screws 13.

A cord or wire 14, extends through the center of the diaphragm 9, to a receiver member 15.

Operatively mounted with reference to the standard 1, is a signalling device 16, having an operating finger piece 17. This may be of any desired form or type so long as the 80 finger piece 17, actuates a striker to sound the gong 18. It is in resonant connection with the diaphragm of the transmitter 4 so that the sound produced by the signalling device is transmitted directly to and causes 85 vibration of the diaphragm 9.

As a companion element to the transmitter there is a receiving head piece such as illustrated in Figs. 3, 4 and 5. This consists of a pair of curved spring bands 19, 20, which are pivotally connected together near their ends so as to be adjustable over the head through said pivotal connections 21, 22. These connections, including the pivots and spring washers 23, will give a resilient gripping action between the head bands 19, 20.

The spring washers and pivots also unite the head bands and clamps 24, 24. These

are of general U shape and are perforated to receive and hold adjusting bars 25. The adjusting bars 25, have U shaped brackets 26, pivoted to the lower ends thereof and 5 also pivoted to the receivers 15.

There is a receiver for each ear and these receivers may be adjusted to any desired position by pressing together the ends of the clamps 24, 24, which hold the rods 25. A 10 further adjustment is secured by the pivotal connection of the U shaped members 26 with the receivers.

It will be noted that there is little to become disarranged in this assembly of the 15 elements and the child may adjust the bands 19, 20, and the rods 25, and receivers 15, without liability of harming the toy. At the same time, these features simulate the usual telephone receiving set.

20 The receivers 15, are similar in construction to the transmitters although of a shape and form to simulate the usual head piece receiving set.

There is a diaphragm 27, clamped between 25 the annular ear piece 28, and the diaphragm chamber casing 29. The latter is pierced as at 30, to provide room for the free attachment of the cord or wire 14, to the diaphragm 27.

30 In Figure 5, in place of a hand standard or handle 1, there is the usual form of desk telephone set comprising a base 31, standard 32, transmitter 33, and receiver 34.

There is also a sounding device 35, the 35 actuating lever of which terminates in a receiver hook 36. A movement of the receiver hook 36, will sound the gong of the signalling device 35, just as the signalling device 16, is sounded by a movement of the 40 finger level 17, of Figures 1 and 2.

Each diaphragm-carrying telephone instrument represented, whether of the form shown in Fig. 1 or in Fig. 3, consists of two shell-like sections,—6 and 7, Fig. 1, and 28, 45 29, Fig. 3—and a vibratory diaphragm between them. This diaphragm is of circular form, and the peripheral edges of the two sections of the casing lie on opposite sides of the edge portion thereof and are united 50 together, confining the diaphragm between them, by folding over the edge of one of the sections. This not only unites the parts of the instrument, but makes a strong reinforced joint where the parts meet and supports the diaphragm, so that it is free to 55 vibrate and act as a sound transmitter, while the edge of the diaphragm serves as a die part against which is spun the turned over edge of the casing section.

60 The shell-like sections of the casing of the telephone instrument both have centrally located openings through them, one to permit the passage of the cord, or wire 14, and the other to freely admit sound waves to 65 the diaphragm. The opening through one

section of the casing of the transmitting instrument shown in Fig. 1,—that through which passes the cord or wire 14—is secured to the support that carries the transmitter, such support surrounding the central opening through the section of the casing to which it is secured, and there being an additional supporting plate member within the chamber of the casing, which is united to the support. 70

It is quite apparent from the above, that children may utilize this toy talking from either end of the connecting cord or wire. In case the child having the head piece with the bands 19, 20, desires to talk back to the 80 child using the transmitter, all that is necessary is to slip the head piece aside and talk into the receiver 15, which is connected with the transmitter 4, or 33. 75

This play may all be controlled by 85 manipulation of the sounding devices. A signal may first be given by the child holding the hand piece 1, or desk set and thereupon a conversation may be opened through the transmitter of the sending set to the 90 receiver of the head set. Response may be made to the sending set from the head set by readjusting the position of the head set and talking into the receiver.

The features of adjustment of the head 95 set are a source of amusement to the child as they may, in play, simulate all the action of the telephone operator who ordinarily employs such an apparatus.

Obviously, the exact details and arrangement of the elements may be modified without departing from the spirit or intent of the invention and various forms of signalling devices might be employed in place of those specifically described. 100

It will be apparent that any combination or duplication of the elements may be used. For instance, two transmission sets, such as illustrated in Figure 1, or Figure 5, may be employed with their signalling device and the interconnected cord or wire or two head sets, as illustrated in Figures 3 and 5, may be employed. In the latter case, the position of the head piece would have to be shifted momentarily, during the conversation of the sender, to the receiver, and when the receiver wishes to reply, his head piece may be shifted while he sends a return message. 110

Thus it will appear that various uses may be made to suit the play of the children using the toy. 115

What I claim is my invention and desire to secure by Letters Patent is:

1. A toy telephone, consisting of a hollow casing in which is supported a vibratory diaphragm, the casing wall on one side of the diaphragm being centrally perforated to permit the passage of a wire leading to the diaphragm, a support for the telephone instrument surrounding the opening through 125 130

the casing wall, to which wall the support is secured, and a supporting plate on the inside of the casing to which the said support for the telephone instrument is connected.

- 5 2. A toy telephone, consisting of a hollow casing in which is supported a vibratory diaphragm, the casing wall on one side of

the diaphragm being centrally perforated to permit the passage of a wire leading to the diaphragm, and a support for the telephone instrument surrounding the opening through the casing wall and secured thereabout.

HAROLD D. ALLEN.
